(57) **CLAIM**

The ornamental design for a portable sheltered bed for a child, as shown and described.

DESCRIPTION

FIG. 1 is a perspective view of a portable sheltered bed for a child showing our new design;

FIG. 2 is a plan view thereof;

FIG. 3 is a side view thereof;

FIG. 4 is a view of the other side thereof;

FIG. 5 is an end view thereof; and,

FIG. 6 is a view of the other end thereof.

The broken lines are for environmental purposes only and form no other part of the claimed design.
